WATER TOY

Jerome A. Bergamini, 10813 Kenneth Ave., Oak Lawn, Ill.

Filed Jan. 4, 1960, Ser. No. 58,891

Term of patent 3½ years

(Cl. D34—15)

FIGURE 1 is a front perspective view of a water toy embodying my new design;

FIG. 2 is an enlarged back elevational view of the design shown in FIG. 1;

FIG. 3 is an enlarged top plan view of the design shown in FIG. 1; and

FIG. 4 is a reduced side elevational view of the design of FIG. 1.

The essential features of my design reside in the portion shown in full lines and comprise two flattened generally cylindrical members having rounded ends and interconnected by a pair of tabs adjacent the ends, said ends flaring outwardly so that they substantially abut, all as shown.

I claim:

The ornamental design for a water toy, substantially as shown and described.
